UNITED STATES PATENT OFFICE.

ALEXANDER C. ELISHEWITZ, OF NEW YORK, N. Y.

DESIGN FOR IMITATION-STRAW-BRAID FABRIC FOR HATS.

Application filed October 19, 1927. Serial No. 23,800. Term of patent 14 years.

To all whom it may concern:

Be it known that I, ALEXANDER C. ELISHEWITZ, a citizen of the United States, residing at New York city, county of New York, and State of New York, have invented a new, original, and ornamental design for Imitation-Straw-Braid Fabric for Hats, of which the following is a specification, reference being had to the accompanying drawing, forming part thereof.

Fig. 1 of the drawing is an enlarged front or face view of a piece of fabric embodying my invention.

Fig. 2 is a similar view of a piece of the same fabric on a smaller scale.

More fully stated, the design is for a hat fabric formed from imitation straw braid.

I claim:

The ornamental design for imitation straw braid fabric for hats, as shown and described.

In witness whereof, I have hereunto set my hand.

ALEXANDER C. ELISHEWITZ.
